UNITED STATES PATENT OFFICE.

JOSEPH F. KURTIS, OF SPRINGFIELD, AND HERMAN F. MILLER, OF DAYTON, OHIO, ASSIGNORS TO GEORGE J. IHRIG AND ERNEST C. IHRIG, OF SPRINGFIELD, OHIO.

MUFFLER FOR GAS OR GASOLENE ENGINES.

SPECIFICATION forming part of Letters Patent No. 718,131, dated January 13, 1903.

Application filed July 21, 1902. Serial No. 116,329. (No model.)

To all whom it may concern:

Be it known that we, JOSEPH F. KURTIS, residing at Springfield, in the county of Clark, and HERMAN F. MILLER, residing at Dayton, 5 in the county of Montgomery, State of Ohio, citizens of the United States, have invented certain new and useful Improvements in Mufflers for Gas or Gasolene Engines, of which the following is a specification, reference being had therein to the accompanying drawings.

This invention relates to mufflers for gas and gasoline engines or for engines of the same general type known as "explosive" or 15 "internal-combustion" engines, although the device is also capable of use in connection with steam-engines or the like.

The invention has for its object to do away with the noise of the exhaust and to render 20 the operation of the engine noiseless in so far as this feature is concerned.

To this end our invention consists in certain 25 novel features, which we will now proceed to describe, and will then particularly point out in the claims.

In the accompanying drawings, Figure 1 is 30 an elevation of a muffler embodying our invention in one form. Fig. 2 is a vertical central sectional view of the same. Fig. 3 is a transverse sectional view taken on the line xx of Fig. 2 and looking in the direction of the arrows. Fig. 4 is a transverse sectional view taken on the line yy of Fig. 2 and looking in the direction of the arrows. Fig. 5 is 35 a sectional view taken on the line zz of Fig. 2 and looking in the direction of the arrows, and Fig. 6 is a detail sectional view taken on the line $z'z'$ of Fig. 2 and looking in the direction of the arrows.

In the said drawings, 1 indicates the exhaust-pipe, which is provided with a check-valve 2, which opens freely to the exhaust, but prevents any reflux of the pressure toward the engine. To this exhaust-pipe is connected the muffler (indicated as a whole by the reference-numeral 3) and comprising a receiving-head 4, an intermediate body portion 5, a discharge-head 6, and an outlet or exhaust head 7. The receiving-head 4 consists

of a cup-shaped or bowl-like portion 8, having 50 a threaded receiving-mouth 9, by means of which it is connected to the end of the exhaust-pipe 1. Beyond this receiving-mouth the part 8 increases in diameter, its larger end being provided with a seat 10 to receive a plate 11, 55 which closes the larger end of the cup or bowl and which is provided with a conical boss 12, extending into the same and having a threaded aperture 13. In this threaded aperture fits the correspondingly-threaded stem 60 14 of the inlet-regulating cone 15, which extends down into the contracted mouth of the receiving-head and serves by its adjustment to regulate the inlet-opening of the muffler, while at the same time its conical shape serves 65 to deflect the exhaust-gases outward, as indicated by the arrows. To render the regulation more effective, the broader end of the cone 15 is provided with a flange 15^a, having notches 15^b, while the bowl 8 is provided with 70 a coöperating shoulder or seat 8^a.

The space within the receiving-head 4 between the bowl 8 and boss 12 is occupied by a series of diaphragms 16, constituting baffle-plates. Any desired number of these diaphragms or baffle-plates may be employed, and in the present instance we have shown four such plates, each extending from the part 8 to the part 12 and closing the passage between the same, except as hereinafter indicated. Each plate is provided at either its inner or outer margin with an opening 17, formed by cutting away the material of the plate and opening up the cut-away portion, as indicated at 18, to form a deflector-plate, 75 standing immediately adjacent to the opening 18 and at right angles to the body of the baffle-plate. These openings 18 are located alternately at the outer and inner margins of the successive plates, so that the exhaust- 80 gases passing through the openings near the outer margins must then pass between the baffle-plates to the openings in the inner margin of the next plate. It will be observed that each deflector-plate stands on that side 85 of its opening toward which the gases must move to reach the opening in the next plate, and said deflector-plates are preferably of

such size as to extend from one plate to the next, as shown. In this way the gases after being caused to diverge outwardly by the regulating-cone 15 are caused successively to 5 pass toward the inner and outer walls of the receiving-head, the deflector-plate serving to divert them from a direct course from one set of apertures to the nearest apertures of the next diaphragm, so as to cause a circulation 10 through all the parts of each space between any two successive baffle-plates or dia- phragms.

The discharge-head 6 is similar in construction to the receiving-head, but reversely arranged. It consists of a cup-like or bowl-like 15 body portion 19, having its larger end closed by a plate 20, having a conical boss 21 extending into the interior of the cup or bowl, said cup or bowl being provided with an outlet-opening 22 in its smaller end. The space 20 between the conical boss and bowl is filled by diaphragms 23, of which any desired number may be employed, they being provided alternately on their inner and outer margins 25 with openings 24 and deflecting-plates 25, formed by bending up the part of the dia- phragm cut away to form the opening.

The receiving and discharge heads are connected by bolts 26 and are spaced apart by a 30 cylindrical casing 27, which fits at one end in the seat 10 of the bowl 8 and at the other end in a corresponding seat 28 in the bowl 19. Within this casing the receiving and discharge heads are connected by means of pipes 35 29, of which any desired number may be employed, three being shown in the present instance. The plate 11 is provided with apertures 30, surrounded by collars 31, while the plate 20 is provided with corresponding ap- 40 pertures 32, surrounded by collars 33. Each pipe 29 is preferably made in two sections, having interposed between their meeting ends a diaphragm 34, having a plurality of relatively small apertures 35, as shown more partic- 45 ularly in Figs. 2 and 3. These diaphragms are held between the meeting ends of the pipe-sections, which are clamped together by the bolts 26, the ends of the pipe-sections fitting in the collars 31 and 33, respectively. In 50 order to form a proper union between the pipes, one section may be provided with an enlarged mouth or bowl 36, into which the end of the other section fits, as shown in Fig. 2.

55 It will be seen that the exhaust-gases after passing through the receiving-head are conducted by the pipes 29 to the discharge-head, passing through the apertured diaphragms 34 on their way, and in passing through the dis- 60 charge-head the gases are again deflected first inward and outward and caused to circulate thoroughly through the spaces between the baffle-plates by reason of the construction of said baffle-plates, the location of their open- 65 ings, and the location of the deflecting-plates.

The outlet-opening 27 of the discharge- head communicates with the outlet-head 7,

which comprises a body portion or wall 37, preferably circular in cross-section and of outwardly-increasing diameter. Internally 7c it is provided with a cup-shaped apertured diaphragm 38 immediately adjacent to the outlet-mouth 27 of the discharge-head, and the diaphragm or baffle-plate 23 within said discharge-head nearest to said outlet is pro- 75 vided with a central discharge-opening 39. (Shown more particularly in Fig. 6.) Out- wardly from the cup-shaped perforated dia- phragm 38 the outlet-head is provided with diaphragms 40 and 41, the former of which 80 has a central opening 42, while the latter is provided with marginal openings 43 and deflecting-plates 44. Outwardly from the dia- phragm 41 there is provided a cup-shaped dia- phragm 45, having marginal serrations 46, 85 forming in conjunction with the body 37 spaces adjacent to the outer wall of the outlet-head, through which the products must pass. Still outwardly beyond the diaphragm 45 is located an apertured plate 47, of less di- 90 ameter than the body 37 of the outlet-head, so that the escaping gases may pass not only through said plate 47, but also around the margins thereof. These several parts are held in position by a threaded rod 48, mounted in 95 the conical boss 21 and extending outward through the outlet-head, the several dia- phragms 38, 40, 41, 45, and 47 being mounted on said threaded rod, which latter is provided with a nut 49, which holds the several dia- 100 phragms in place and also holds the conical body 37 in place by reason of the pressure of the margins of the diaphragms on the inner wall of said body. The threaded rod 48 car- ries at its outer end an exhaust-regulating 105 cap or closure 50, having a central threaded socket 51 to receive the end of the rod and having outlet-apertures 52, grouped around said central socket. The cap or closure 50 is provided with a flange 53, extending into the 110 body of the outlet-head and having outlet- apertures 54 therein, which may be closed to a greater or less extent or entirely by turn- 115 ing the cap upon the threaded rod, so as to cause the body of the outlet-head to extend 120 over said apertures to a greater or less ex- tent. The exhaust-gases after passing from the discharge-head are further deflected and subdivided in their passage through the outlet-head, so that their final escape through 125 the apertures 52 and if desired or necessary also through the apertures 53 is noiseless.

It will be observed that we have provided a muffler having means for regulating the admission of the exhaust-gases and also means 125 for regulating the escape of said gases after passing through the muffler, so that by a proper adjustment of these regulating de- 130 vices the muffler may be caused to operate successfully under varying conditions. By 130 reason of the retardation and subdivision of the exhaust-gases in their passage through the muffler their final exit is practically noise- less, while at the same time the structure is

such that no back pressure is exerted upon the engine. The entire structure is so organized that it may be readily taken apart and as readily assembled for purposes of inspection and repair.

5 We do not wish to be understood as limiting ourselves strictly to the precise details of construction hereinbefore described, and shown in the accompanying drawings, as it is 10 obvious that these details may be modified without departing from the principle of our invention.

Having thus fully described our invention, what we claim as new, and desire to secure 15 by Letters Patent, is—

1. A muffler comprising a receiving-head adapted to be connected with the exhaust-pipe and provided with internal baffle-plates and with means for regulating the admission 20 of the exhaust-gases, a discharge-head also provided with internal baffle-plates, a plurality of pipes connecting the receiving and discharge heads, and means for regulating the escape of the exhaust-gases after passing 25 through the discharge-head, substantially as described.

2. A muffler comprising a receiving-head adapted to be connected with the exhaust-pipe and provided with internal baffle-plates 30 and with means for regulating the admission of the exhaust-gases, a discharge-head also provided with internal baffle-plates, a plurality of pipes connecting the receiving and discharge heads, each pipe being provided 35 with a perforated diaphragm, and means for regulating the escape of the exhaust-gases after passing through the discharge-head, substantially as described.

3. A muffler comprising a receiving-head 40 adapted to be connected with the exhaust-pipe and provided with internal baffle-plates and with means for regulating the admission of the exhaust-gases, a discharge-head also provided with internal baffle-plates, a plurality of pipes connecting the receiving and 45 discharge heads, and an outlet or exhaust

head connected with the outlet of the discharge-head, provided with internal baffle-plates and having an adjustable cap or closure to regulate the final escape of the exhaust-gases, substantially as described.

4. In a muffler, a head comprising a bowl-shaped body having relatively large and small openings at its opposite ends, a plate closing the outer end having openings and a central 55 conical boss extending into the bowl, and annular baffle-plates fitting at intervals between the boss and bowl and provided alternately at their inner and outer margins with cut-away portions, and upstanding deflecting- 60 plates adjacent to the margins of the openings toward which the gases move, substantially as described.

5. In a muffler, the combination, with a receiving-head having a bowl-shaped body and 65 an apertured cover with a central boss and separated diaphragms having openings at their alternate margins and adjacent deflecting-plates, of a conical regulating and deflecting cone adjustably mounted in the inlet-opening 70 of the receiving-head, a similar reversely-arranged discharge-head provided with similar baffle-plates, pipes connecting the receiving and discharge heads and provided with apertured diaphragms, an outlet or exhaust 75 head connected with the outlet-opening of the discharge-head and provided with internal baffle-plates, and an adjustable cover or closure for the discharge-mouth of the exhaust-head to regulate the outlet thereof, 80 substantially as described.

In testimony whereof we affix our signatures in presence of two witnesses.
